INVENTOR

BY Victor J. Evans

ATTORNEY

WITNESS:

UNITED STATES PATENT OFFICE

AUGUST ANDERSON, OF SHOSHONE, WYOMING

WIRE STRETCHER

Application filed October 7, 1925. Serial No. 61,059.

This invention relates to a wire stretcher, the general object of the invention being to provide means whereby any amount of slack can be taken out of a wire by alternately engaging a pair of grips with the wire and by simply moving a dog from one position to another and turning over the body of the device, so that the chain which carries the grips has its movement reversed.

Another object of the invention is to provide a holding member which can be easily and quickly put in position and which will release the wire by slackening the wire, as it will grip and hold a wire without a binding action between the parts which tends to make the releasing of the wire difficult.

A further object of the invention is to make the chain wheel of great strength so that there is no danger of its breaking, and of such construction that it will grip the chain without danger of the chain slipping.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view showing the device in use.

Figure 2 is a longitudinal sectional view through the body of the device.

Figure 3 is a section on line 3—3 of Figure 2.

Figure 4 is a section on line 4—4 of Figure 2.

Figure 5 is a sectional view through the chain wheel.

Figure 6 is a view of the holding or gripping member.

Figure 7 is a view of the gripping lever of the holding member.

The body A of the device is formed of a frame 5 in which is journaled a shaft 6, the ends of which extend from the frame and are shaped to receive the socket part of a handle

7 so that the shaft can be turned by hand. A chain wheel 8 is connected with the shaft and is located between the two parts of the frame. This wheel is formed with the projections 9 for engaging the spaces formed by the links of the chain 10 and the pairs of spaced projections 11 which form recesses for receiving the edges of the links, as clearly shown in Figure 2. The edges of the portions forming the projections 9 are curved, as at 12, to receive the curved end portions of the links. Thus when the wheel is turned, the projections engaging alternate links of the chain will cause the chain to pass through the device. A double pawl 13 is pivoted in the frame and prevents retrograde action of the chain wheel. By reversing this dog, the chain wheel can be rotated in an opposite direction. The pawl is held in either one of its two positions by means of a spring plunger 14 carried by the frame and engaging the wedge shaped center of the pawl. Spacer members 15 are placed in the frame to prevent side play of the pawl, these members having portions bent over the parts of the frame, and the pivot pin 16 of the pawl passes through said members.

A swivel 17 is placed in one end of the frame and a chain 18 is connected with this swivel. A gripping member B is fastened to the end of this chain and similar members C and D are attached to the end of the chain 10.

Each member comprises an L-shaped body 19, which is provided with a curved handle part 20 at the junction of its two arms and which has an eye 21 at the extremity of one arm for receiving a terminal link of a chain. The other arm is of greater dimensions and has a beveled end 22. A lever 23 is pivoted to the member 19 by a pin 23', and the extremity of this lever is bent over to form a groove 24, with a slot 25 in the bent over portion, the part to one side of the slot being bent outwardly to form an ear 26.

The wire to be gripped is placed in the groove 24 and then bent and passed through the slot 25 and then the lever swung against the member 19 so that the beveled part 22 will enter the groove 24. Thus a tension on the parts will cause the lever 23 to clamp the

wire between itself and the end 22 of the member 19, and the greater the pulling force, the greater will be the clamping action. As soon as the wire is slackened, however, the lever 23 will swing away from the member 19 so that the wire can be easily released. One of the gripping members on chain 10 is fastened to one wire and the gripping member B on chain 18 is fastened to the second wire.

10 Then by turning the shaft by means of the handle 7, the chain will be pulled through the device, so that the two wires will be brought towards each other. When the member D reaches the body A, the member C is

15 gripped on the wire and the member D released. Then the pawl is reversed, the handle 7 placed in engagement with the other end of the shaft and the body A turned over so that when the handle is turned, the chain will

20 be fed through the device in an opposite direction and take up further of the slack in the wires. This operation is repeated until the wires are sufficiently taut.

The device is very compact, can be manufactured to sell at low cost and the gripping members can be quickly and easily placed on the wires and just as easily released therefrom.

What I claim is:—

30 A wire stretcher including a chain wheel mounted for rotation, a chain, said wheel comprising opposed side plates each of substantially triangular contour providing corner projections, the corner projections of the respective plates being arranged in confronting relation, said wheel also including center projections arranged between the corner projections and the triangular-shaped side plates and extending an appreciable distance beyond the edges of said triangular plates to receive the links of the chain, the side edges of the triangular-shaped plates being of a length substantially equal to the length of the link, whereby the latter lies flat upon the 45 adjacent side edges of the triangular-shaped plates throughout their length while engaged by the adjacent center projection.

In testimony whereof I affix my signature.

AUGUST ANDERSON.
